UNITED STATES PATENT OFFICE.

WILLIAM JOHN LUXMOORE, OF LONDON, ENGLAND.

HEEL OF BOOTS AND SHOES.

1,261,569.

Specification of Letters Patent.

Patented Apr. 2, 1918.

Application filed July 24, 1914. Serial No. 852,821.

To all whom it may concern:

Be it known that I, WILLIAM JOHN LUXMOORE, a subject of the King of Great Britain and Ireland, residing at London, England, have invented Improvements Relating to the Heels of Boots and Shoes, of which the following is a specification.

This invention has reference to heel pads of the kind consisting of rings or equivalent of rubber or rubber composition shaped to fit and adapted to be sprung over center pieces of suitable material fixed to the top lifts of the heels of boots and shoes, the object being to enable the heel pads to be easily attached and detached and the heel pads of a pair used alternatively upon the right or the left boot or shoe heel and the wear of the pads thus more evenly distributed.

For this purpose, the ring-like heel pads of a pair are made exactly alike and the external outline and the aperture in each of them are symmetrical with respect to a central longitudinal plane, the aperture being preferably dovetailed or otherwise formed so as to engage the correspondingly shaped center pieces fixed to the boot or shoe heels.

In the accompanying illustrative drawings,

Figure 1 is an underside view of a detached heel pad;

Fig. 2 a longitudinal section showing the pad applied to a boot heel by engagement with the center piece that is secured to the boot heel.

Fig. 3 is an underside view of the center piece;

Fig. 4 is a similar view to Fig. 2 showing the center piece with pins engaging the ring like pad;

Figs. 5 and 6 are similar views to Figs. 1 and 2 illustrating a modification;

Fig. 7 is a similar view to Fig. 1 illustrating another modification.

Fig. 8 illustrates an underside view of a heel pad which is not formed as a complete ring of rubber, but has its rubber sides connected at the front by a wire *f*, or wires, so as to form a complete ring.

As will be seen the external outline of the rubber pad *a* and its aperture *b* are symmetrical with respect to a central longitudinal plane *c*, the front margin of the aperture being at right angles to the said plane, the side margins parallel and the rear margin

constituted by surfaces converging upon said plane at equal angles thereto. The marginal surfaces of the aperture *b* are dovetailed as are also the corresponding parts of the center piece *d* which is nailed to the heel, or may be screwed or otherwise secured thereto or made in one therewith. In some cases pins may project from the front and rear faces of the center piece as shown in Fig. 4.

The heel pads can be easily attached or detached by springing the rubber over the center pieces, the pins referred to, if these be provided, entering the rubber when the pads are sprung over the center pieces and still further securing the pads against accidental detachment. It will be observed that the normal diameter of the aperture *b* is less than that of the projection *d*, so that in attaching the pad it is necessary to stretch it slightly to attach it over the projection *d* and so that also when the pad is attached the tendency to contract will hold it securely in the wedge-like recess formed by the bottom of the heel and the undercut edge of the projection *d*.

In the modification shown in Figs. 5 and 6 accidental detachment is obviated by providing across the angles of the aperture *b* thin webs *e* which take into recesses at the corners of the center piece *d*, between it and the face of the heel. In some cases these webs may be extended around the aperture as indicated by dotted lines.

In Fig. 7 the rear wall of the aperture is curved instead of being angular but as the aperture is still symmetrical with regard to the central longitudinal plane the heel pads can be changed over from the one boot to the other.

This is also the case with the arrangement shown in Fig. 8 in which the wire *f* takes into a recess or groove in the front portion of the center piece.

As will be understood, the shape of the heel pad ring shown is capable of modification so long as it is such that it can be fitted to either heel of a pair of boots or shoes so as to be fixed in relation thereto.

What I claim is:

1. The combination of a heel provided with a projection on its wearing face, this projection being undercut around its edge and provided with recesses, and a ring-like pad of elastic material provided with an aperture shaped to fit the said projection and

being symmetrical with respect to the central longitudinal plane, the pad being further provided with webs extending into said recesses, and the normal diameter of said aperture being less than that of the projection, for the purpose set forth.

2. The combination of a heel provided with a projection on its wearing face, this projection being undercut around its edge, 15 said projection having recesses at its corners, and a ring-like pad of elastic material provided with an aperture shaped to fit the said projection and being symmetrical with re-

spect to the central longitudinal plane, and having webs to engage in said recesses, and 15 the normal diameter of said aperture being less than that of the projection, for the purpose set forth.

Signed at 10 New Court, Lincolns Inn, London, England, this fifteenth day of July, 20 1914.

WILLIAM JOHN LUXMOORE.
